HOWARD J. MURRAY, OF BROOKLYN, NEW YORK, ASSIGNOR TO HENRY SIEBEN, OF HADLEY, NEW YORK

AUTOMATIC GAS SHUT-OFF

Application filed November 30, 1926. Serial No. 151,820.

The invention relates in general to a self-closing shut-off valve particularly of the type of valves commonly used in shutting off a gas or liquid flow to a building, and 5 the invention relates to that type of such valves which are either manually actuated at will or automatically actuated by a rise of temperature in the vicinity.

The primary object of the invention is to 10 provide an extremely simplified form of valve construction which will possess all of the advantages inherent in known forms of such valves, such as positive actuation and firm seating of the valve, and at the same 15 time to provide a commercially perfected structure in which the several operable parts are minimized in number, simplified and protected from accidental or unintentional operation.

20 The invention features the employment of a pull member for the purpose of holding a spring actuated self-closing valve in its normal position off its seat, and in which the parts are organized so that the valve may be 25 moved to open position, and held in open position by locking the pull member under tension at a remote point.

Another object of the invention is to provide 30 as part of the pull member a fusible link and to minimize the tension on the pull member, including the fusible link, while permitting a powerful spring actuation of the valve in moving into closed position when tension is released on the pull member.

35 Various other objects and advantages of the invention will be in part obvious from an inspection of the accompanying drawings and in part will be more fully set forth in the following particular description of 40 one form of device embodying the invention, and the invention also consists in certain new and novel features of construction and combination of parts hereinafter set forth and claimed.

45 In the drawings:

Fig. 1 is a combined view of a valve casting shown in side elevation with parts broken away, of a remote control casing shown in vertical section and a connector between 50 the casting and the casing, coacting to illus-

trate a preferred embodiment of the invention;

Fig. 2 is a horizontal sectional view taken axially of the valve stem through the mechanism containing compartment of Fig. 1; 55

Fig. 3 is a horizontal sectional view through the control casing and taken on the line 3—3 of Fig. 1.

In the accompanying drawing and referring 60 particularly to Fig. 1 there is disclosed two spaced apart units, one constituting a casting 10 containing a valve and an operating mechanism therefor and the other constituting a casing 11 constituting a remote 65 control station.

Referring to the casting 10 there is disclosed a valve containing compartment 12 and a valve operating mechanism containing compartment 13 separated from each other by a partition 14. Flow 70 through the valve compartment is controlled by a self-closing valve 15 shown in open position and in dotted lines in Fig. 1 and in full lines in Fig. 2. The valve is adapted to be moved into closed position engaging the seat 16, shown in dotted lines in Fig. 1 to intercept the flow through the casting. It is understood that the parts thus far described are of somewhat conventional design and constitute part of a flow line through which 75 gas or other fluids move as is indicated by the arrows in Fig. 1.

The valve is provided with a stem 17 which projects through the partition 14 and is intruded into the compartment 13. Secured to the outer end of the valve stem is a grooved pulley 18. Coiled on the portion of the stem between the pulley 18 and the wall 14 is a relatively powerful spring 19 one end 80 of which is secured at 20 to the wall 14 and the other end is secured by means of pin 21 to the side of the pulley 18 and spaced inwardly from the periphery 22 of the pulley as is clearly indicated in Fig. 2. The spring 85 is so disposed that when released it moves 90 the valve from the open position illustrated into firm closing engagement with its seat.

The part of the casting 10 which forms the mechanism containing compartment 13 is provided on its upper side with a tubular 100

extension 23 provided with a plurality of air vents 24 to air cool the contents thereof. From this construction it is understood that the compartment 13 and its contents are removed from the presence of the flow passing the valve.

The valve is moved to open position and held in open position by a flexible pull member 25 one end portion 26 of which is secured 10 to the periphery 22 of the pulley as by inturning the same as shown at 27 (Fig. 1). The parts are so disposed that when tension is released on the pull member as hereinafter described the flexible part 26 will be wound 15 onto and into the groove forming the periphery of the pulley. Forming part of the pull member within the housing and air cooled extension 23 is a fusible link 28 disposed so as to be protected by the casting and 20 at the same time disposed in the path of cooling air passing through the vents 24. The upper portion of the pull member beyond the fusible link passes through an opening 29 in the end of the extension 23, 25 extends between the units, is passed through an opening 30 in the bottom of the casing 11 and is disposed in position to be engaged by a locking or holding member 31 contained in the casing 11.

30 In order to minimize the constant tension on the pull member while holding the valve open, the end portion 26 is secured to the pulley at a greater distance from the axis of rotation of the shaft 17 than the point 21 at 35 which the spring engages the pulley to rotate the shaft. In order further to minimize the tension on the fusible member, it is shown to be formed of two fusible wires 32 and 33 arranged abreast and secured at opposite ends 40 respectively to the end portions of the flexible members by means of equalizing brackets 33 and 34.

45 From this structure it is appreciated that the strain on the link as a whole is divided between the wires 32 and 33 and the equalizing brackets which are pivoted to the flexible ends tend to distribute the strains equally to the two wires. The readily releasable locking means 31 comprises a boss 35 projecting 50 from the rear wall 36 of the casing and forms the fixed element of a clutch. The boss is provided with bifurcated ears 37 between which is pivotally supported a cam 38 on pin 39. The cam constitutes the movable element 55 of the clutch and is provided with a forwardly extending finger piece 40 by means of which the cam can be readily rotated to and from its clutching position. The flexible member is passed between the periphery of 60 the cam and the forward face of the boss 35 and the parts are so positioned that when the finger piece 40 is in the position shown in Fig. 1, the cam is in firm holding engagement with the pull member and acts there- 65 through to hold the valve in the open position

as shown in Fig. 1. In order to prevent the flexible member from slipping out of the cam clutch it is provided with a pull knob 41. The casing 11 is provided with a hinge cover 42 secured conventionally by a seal 43 and in 70 other respects this control station is of conventional design.

In operation it will be understood that the setting of the valve is controlled from the remote station by opening the cover, pulling 75 on the pull member with the locking device released, and when the valve is in its fully opened position, the finger piece of the locking device is raised thus clutching the pull member and holding the same under tension 80 of the spring 19. Should it be desired to close the valve, the operator simply trips the locking device by lowering the finger piece from the position shown in Fig. 1 and the valve is automatically moved under tension 85 of the spring into firm closing engagement in its seat.

While I have shown and described, and have pointed out in the annexed claims, certain novel features of my invention, it will 90 be understood that various omissions, substitutions and changes in the form and details of the device illustrated and in its operation may be made by those skilled in the art without departing from the spirit of the invention.

Having thus described my invention, I claim:

1. In a device of the class described, the combination of a casting provided with a valve containing compartment and a mechanism containing compartment, with a fluid tight separating partition therebetween, a valve mounted in the valve containing compartment, a valve stem secured to the valve 100 and projecting therefrom through said partition and into the mechanism compartment, resilient means in the mechanism compartment engaging the projecting portion of the stem and tending to move the valve into closed 105 position and means including a manually actuated member extending from an external point into the mechanism compartment engaging the valve stem and adapted to move the valve off its seat against the resistance of 110 said resilient means.

2. In a device of the class described, the combination of a casting provided with a valve containing compartment and a mechanism containing compartment, with a fluid tight separating partition therebetween, a valve mounted in the valve containing compartment, a valve stem secured to the valve 120 and projecting therefrom through said partition and into the mechanism compartment, resilient means in the mechanism compartment engaging the projecting portion of the stem and tending to move the valve into closed 125 position and means including a manually actuated member extending from an external 130 point into the mechanism compartment engaging the valve stem and adapted to move the valve off its seat against the resistance of

5 point into the mechanism compartment and engaging the valve stem and adapted to move the valve off its seat against the resistance of said resilient means, and the portion of the manually actuated member within the confines of the mechanism compartment including a fusible link.

10 3. A fluid flow controlling apparatus including a casing having a mechanism containing compartment, a valve stem intruded into said compartment, means in said compartment tending to move said stem in one direction manually actuated means operable from a point exterior of the casing and engaging said stem for moving the stem in the opposite direction, the portion of said means within the compartment including a fusible link and said casing provided with air openings to permit the air cooling of the 15 fuse in the chamber.

20 4. In a device of the class described, the combination of a casing having a mechanism containing chamber, a valve in the casing provided with a valve stem intruded into said chamber, a pulley wheel secured to the stem, a spring coiled about the stem and tending to move the valve onto its seat, a flexible valve holding member having an end engaging the pulley wheel and means normally engaging 25 said holding member in position so as to hold the valve off its seat, said member capable when released of being wrapped on to the pulley wheel under action of said spring when closing the valve.

30 5. In a device of the class described, the combination of a valve provided with a valve stem mounted for rotary movement, a spring acting on the stem and tending to move the valve into closed position, means including 35 a pull member acting on the valve stem to rotate the same into position to open the valve and a readily releasable holding means engaging the pull member at a point remote from the valve to secure the valve in open position 40 against the tension of said spring.

45 6. In a device of the class described, the combination of a valve provided with a stem mounted for rotary movement, a spring having one end secured to the stem relatively close 50 to the axis of rotation of the stem and acting thereon with a short, powerful leverage effect and adapted to rotate the stem and thus close the valve onto its seat, a pull member having one end secured to the stem at a 55 greater distance from the axis of rotation of the stem and adapted to act thereon with a longer leverage effect, and remote holding means for engaging the pull member in securing the valve in open position and against 60 the tension of the closing spring.

65 7. In a device of the class described, the combination of a valve provided with a stem mounted for rotary movement, a spring having one end secured to the stem relatively close 70 to the axis of rotation of the stem and

75 acting thereon with a short, powerful leverage effect and adapted to rotate the stem and thus close the valve onto its seat, a pull member having one end secured to the stem at a greater distance from the axis of rotation of the stem and acting thereon with a longer leverage effect, said pull member including within its length a fusible link, and remote holding means for engaging the pull member in securing the valve in open position and against the tension of the closing spring.

80 8. In a device of the class described, the combination of a casting provided with a valve containing compartment and a mechanism containing compartment, a valve in the first named compartment for controlling the flow therethrough, and a valve closing means in the second compartment exposed for air cooling, a control casing spaced from the said casting, locking means housed within the control casing, a flexible connector extending between the casting and the casing with one end secured to the valve closing means and adapted to act thereon to move the valve into open position, and the other end engaged by said locking means and acting normally to lock the valve in open position.

85 9. In a device of the class described, the combination of a casting provided with a valve compartment and a mechanism containing compartment, a valve in the valve compartment for controlling the flow therethrough, means acting on the valve and tending to move the same towards its seat, a pull member normally under tension extending from a remote control point into the mechanism containing compartment for holding the valve off its seat, the portion of the pull member within said mechanism containing compartment including a fusible link housed within and protected by the casting and removed from the path of the flow past the valve.

90 Signed at New York in the county of New York and State of New York this fifth day of November, A. D. 1926.
